UNITED STATES PATENT OFFICE.

LIONEL D. SAXTON, OF PHILADELPHIA, PENNSYLVANIA, ASSIGNOR TO
LOUIS GOODMAN, OF NEW YORK, N. Y.

SOFT-TREAD HORSESHOE.

SPECIFICATION forming part of Letters Patent No. 586,696, dated July 20, 1897.

Application filed October 12, 1896. Serial No. 608,547. (No model.)

To all whom it may concern:

Be it known that I, LIONEL D. SAXTON, a citizen of the United States, residing in the city and county of Philadelphia, State of Pennsylvania, have invented a new and useful Improvement in Horseshoes, which improvement is fully set forth in the following specification and accompanying drawings.

My invention consists of a horseshoe or other animal shoe which is provided on its under face with pads or cushions which are seated in grooves, alternating with which is a neck or necks, which pads or cushions and neck or necks constitute the tread of the shoe, thus preventing slipping, providing a balance for the shoe, and increasing the strength thereof, while equalizing the wear of the tread.

Figure 1 represents a bottom view of a horseshoe embodying my invention. Fig. 2 represents a vertical section thereof on line *x-x*, Fig. 1. Fig. 3 represents a transverse section on line *y-y*, Fig. 1. Fig. 4 represents a vertical section of a portion of another form of my invention. Fig. 5 represents a bottom view of a portion of a modification.

Similar letters of reference indicate corresponding parts in the several figures.

Referring to the drawings, A designates a horseshoe in the under face of which are recesses or grooves B, which extend in the longitudinal direction of the sides thereof.

C designates a downwardly-projecting neck which occupies a position on the under face of the shoe at the toe portion thereof, the same being solid with said portion and joining the walls of the adjacent ends of the grooves B, it being seen that the neck is between the said grooves and closes the front ends thereof.

Within the grooves B are seated the upper portions of the pads or cushions D, which are formed of alternate layers of canvas or other fabric and elastic material, such as rubber or rubber product, the sides of said pads or cushions being pressed in or pinched by the depending lips E on the walls of the grooves, said lips being inturned, so as to forcibly engage with the contiguous parts of the sides of the pads or cushions and compress the same, thus firmly holding the pads in position.

In Fig. 4 the neck F is shown as a separate piece of metal inserted in the cavity G of the toe portion of the shoe and held therein by a dovetailed joint or otherwise.

It will be seen that the tread which is presented to the ground, roadway, &c., is partly pliable and partly rigid, by which provision the wearing capacity of the tread is increased, while admirable non-slipping means are provided, and at the same time the neck C breaks the continuity of the grooves B and increases the strength of the tread and provides a balance for the shoe and equalizes the wear on said tread.

Above the tread is a horizontally-projecting rim H, from whose outer face depends the vertical lip J, which is adapted to engage with the ground when the hoof is presented at an angle thereto, so as to take firm hold of the same and further prevent slipping.

If desired, the number of necks may be increased, as shown in dotted lines in Fig. 1 and full lines in Fig. 5, in which case the continuity of the groove on each side of the shoe is broken and the necks join the walls of the grooves as thus formed, as shown at C' C² in said Fig. 5.

Having thus described my invention, what I claim as new, and desire to secure by Letters Patent, is—

1. A horseshoe having grooves in its under face with a separating downwardly-projecting neck, integral with the body of the shoe, and a horizontally-projecting rim with a depending lip, the walls of said grooves having depending lips.

2. A horseshoe having the grooves B in its under face extending from the heel to the toe portion thereof, the downwardly-projecting toe-piece C separating the front ends of said grooves, cushions held in said grooves, and the horizontal rim H having the downwardly-projecting lip J.

3. A horseshoe having the grooves B in its under face extending from the heel to the toe portion thereof, the downwardly-projecting toe-piece C separating the ends of said grooves, the horizontal rim H having the downwardly-projecting lip J, and the cushions of fibrous material and rubber held in said grooves.

LIONEL D. SAXTON.
